CORONA SHIELD

George M. Ruoff, Baltimore, Md., assignor to
 Locke Insulator Corporation, Baltimore, Md., a
 corporation of Maryland

Application August 15, 1939, Serial No. 290,286

2 Claims. (Cl. 174—144)

The invention relates to corona shields and more particularly to corona shields in connection with strain and suspension clamps.

The principal object of my invention, generally considered, is to provide a shielding member adapted to be secured to a clamp and to surround the clamp body so as to suppress corona charges from the sharp projecting portions of the clamp structure.

Still another object of the invention is to provide a corona shield which may be readily and conveniently formed from stock material having a continuous body portion in loop form, the opposite end of the loop being flattened and perforated to receive the securing means.

To these and other ends the invention relates to various modifications of the construction shown on the accompanying drawings in which:

Figure 1 is a side elevational view showing my improved form of corona shield assembly with a suspension clamp, the latter being illustrated by dot and dash lines.

Figure 2 is a top plan view of the shield member shown in Figure 1.

Figure 3 is a side elevational view of a corona shield adapted to be assembled with a strain clamp, the latter being illustrated by dot and dash lines.

Figure 4 is a top plan view of the construction shown in Figure 3.

Throughout the specification and drawings like parts are designated by like reference characters.

Owing to the constantly increasing use of radio receiving sets in all sections of this country it has become of vital importance to provide for the suppression of noises emanating from transmission lines. It has been found that one of the sources of radio interference in connection with transmission lines is in the lack of shielding adjacent the support for the conductor. All clamps, whether of the suspension or the strain variety, involve a plurality of nuts and bolts, the sharp edges and corners of which become corona discharge points. In addition, in suspension clamps it is common to arch the ends of the keeper away from the conductor so as to prevent damage to the conductor during the oscillation of the latter and these arched up ends of the keeper also form corona discharge points.

It has been common to provide in connection with insulators strings, grading shields and arcing horns, the former acting to equalize the impressed voltage through the string of insulators and the latter acting as discharge points for the surges over the conductor. Since both arcing

horns and grading shields are spaced above the associated clamps they cannot and do not effectively control corona discharges from the clamp proper, and it is the purpose and object of this invention to provide a shield which can be positioned adjacent the clamp, the shield lying substantially in the plane of the clamp, the body of the shield being arranged substantially parallel to the plane of the conductor and extending both above and below the body of the clamp so as to prevent corona discharge from any portion of the clamp and in this manner silence the clamp so far as radio noises are concerned.

Referring now to the drawings, the numeral 1 designates a corona shield which may be and preferably is formed as a loop 2 having the end portions thereof flattened, as shown at 3, and perforated, as shown at 4, in order that the pivot bolt 5, by which the parts of the suspension clamp 6 are pivotally connected, may be passed through the ears or flattened portions 3 so as to firmly unite the shield to the clamp body. The loop portion is adapted to extend both above and below the conductor receiving portion 7 of the suspension clamp and by extending the arms 8 which form the upper portion of the loop at an angle to the arm 9 forming the lower portion of the loop, the shield is spaced from the conductor at points where the arms 8 and the arm 9 merge. The shield being positioned both above and below the clamp body and being adapted to intersect the plane of the conductor and at the same time is maintained substantially in the plane of the clamp body, effectively acts to suppress corona discharges and thereby silences the clamp and prevents any interference between this portion of the transmission line and the radio sets.

As shown in Figures 3 and 4, I use substantially the same means for suppressing corona discharges from strain clamps and in this embodiment of the invention the corona shield is substantially triangular in outline, the base 10 of the triangle preferably extending substantially parallel to the clamping portion 11 of the strain clamp 12, one of the sides of the triangle 13 extending upwardly and being provided with a perforated ear 14, the other arm 15, for the major portion of its length, extending parallel to and preferably in contact with the upper surface 16 of the clamp. The arm 15 is connected to the base 10 by a semi-circular portion 17, said portion being spaced above the plane of the arm 15 so that the conductor, at its point of exit from the upper portion of the clamp, will not contact the portion 17 of the shield. The arm 15 is also provided with an ear 18 having an

opening therein and the bolt 19 by which the clamp is connected to its support is also adapted to pass through the ears 14 and 18 for maintaining the shield in assembled position with the clamp.

5. The function and purpose of the shield of Figures 3 and 4 are identical with that of the shield of Figures 1 and 2 and since the latter have been fully described it is not essential to repeat this description for these figures.
10. Having thus described my invention what I claim and desire to secure by Letters Patent is:
  1. The combination with a high tension line conductor, of a clamp therefor, means for connecting said clamp to one of the series of connected insulators, and a corona shield connected to said clamp, said shield being positioned substantially in a vertical plane passed through the

longitudinal axis of said clamp, opposite portions of said shield lying on opposite sides of said conductor.

2. The combination with a high tension line conductor, of a clamp therefor, means for connecting said clamp to one of a series of connected high tension insulators, and a corona shield comprising a loop member of substantially uniform cross-section, the free ends of said loop being positioned on opposite sides of said clamp and connected thereto, opposite portions of said loop lying on opposite sides of said conductor, the vertical plane passing through said loop being substantially parallel to the vertical plane passing through the longitudinal axis of said clamp. 15

GEORGE M. RUOFF.
